United States Patent Office

Des. 211,256
Patented June 4, 1968

211,256

SPEAKER BAFFLE

Aston L. Moore, 220 Hammond Place,
South Bend, Ind. 46601

Filed Nov. 1, 1967, Ser. No. 9,238

Term of patent 14 years

(Cl. D26—14)

FIG. 1

FIG. 2

FIG. 3

Fig. 4

Fig. 5

Fig. 6

Fig. 7

FIGURE 1 is a top perspective view of a speaker baffle showing my new design;

FIGURE 2 is a side elevational view thereof, the opposite side being a mirror image thereof;

FIGURE 3 is a bottom view thereof as seen from the cutting line III—III in FIGURE 2;

FIGURE 4 is a top perspective view of a modification of my new design;

FIGURE 5 is a side elevational view thereof, the opposite side being a mirror image thereof;

FIGURE 6 is a top plan view thereof; and

FIGURE 7 is a bottom view thereof, as seen from the cutting line VII—VII in FIGURE 5.

I claim:

The ornamental design for a speaker baffle, as shown and described.
